AUTOMATIC LIVESTOCK BARN EVACUATION DEVICE

Maurice M. Breen, 17 Maple St., Malone, N.Y.
Filed May 10, 1961, Ser. No. 109,180
4 Claims. (Cl. 119—112)

The present invention relates to a device to automatically evacuate a building holding livestock.

An object of the present invention is to provide a device to automatically empty a barn of livestock when a fire in the barn is detected, it being known that most livestock, if not all livestock, will not readily leave a burning environment but will panic and attempt to return to the burning structure rather than be led to relatively unfamiliar but safe surroundings.

Another object is to provide a device which will automatically lead livestock to safety from an endangered environment without human assistance, and at such a rate of speed as to preclude any damage or fatality to the livestock.

A further object is to provide a livestock evacuation system which is foolproof in operation, one simple in structure and without expensive appurtenances needed for its operation, and one highly effective in action.

With these objects in mind, the invention is described as follows, and in the light of the teachings of the attached drawings, in which:

FIG. 1 is a side elevational view,

FIG. 2 is a top plan view of the assembly of FIG. 1,

FIG. 3 is a view, enlarged, of a portion of the assembly shown in FIG. 1, showing in dotted lines the disconnect movement of the stanchion release means,

FIG. 4 is an isometric view of the cable arrangement shown somewhat schematically with parts broken away, and

FIG. 5 is an isometric view of a part of FIG. 4 showing one of the stanchions drawn to the evacuation cable as in actual use.

With reference to the drawings in detail, the numeral 10 designates a barn or other holding place for livestock. At a location remote from the barn 10 is a power station 11. Overhead in the barn 10 and extending to station 11 is an endless cable 12 traveling over pulleys 13 and 14. A shaft 15 carries the pulley 14 and mounted on the shaft 15 is a drum 16 having a friction drag lever 17 in engagement therewith.

The lower flight 9 of the cable 12 has fixed to it a plurality of rings 18 arranged in spaced relation therealong. A pull or evacuation cable 19 has an end portion wound on a winch 20 mounted on the station 11 and driven by an electric motor 21.

The cable 19 has the free end fixed to a rod 22 by means of an eye formation 23 on one end of the rod 22. The rod 22 has fixed to it, at a distance rearwardly of the formation 23, a hook bar 24. At spaced intervals on the rod 22, rearwardly of the bar 24, are secured the ends 25a of a plurality of lead cables 25.

In the barn 10, along one or both sides, are stanchions 26 each having its lower end provided with an eye formation 27 receiving a release member 28, as shown in FIG. 1. The upper end of each stanchion 26 is similarly provided with an eye formation 29 receiving another release member 30. The members 28 and 30 are secured to a frame 31 which is movable between the full line position and the dotted line position in FIG. 3.

A bar 32 extends horizontally across the barn 10 and is secured to the frame 31 (FIG. 2) and a lever device 33 has its lower end pivotally connected at 34a to a wall 34 of the barn 10 and its upper end engageable in the hook bar 24. The lever device 33 engages the bar 32

2

responsive to movement, toward the right in FIG. 3, of the cable 19 and associated rod 22. This results in movement of the frame 31 to disengage both the upper and lower release members 30 and 28, respectively, from the adjacent stanchion eye formation 29, 27.

A thermal responsive switch 35, in an appropriate place in the barn 10, is electrically in circuit with the motor 21 and a source of current.

Weights 36 are removably secured to the drag lever 17, for adjusting the drag on the cable 12.

The operation of the evacuation device is as follows. With an animal in each stanchion 26, upon overheating of the thermal responsive switch 35, due to fire, the motor 21 is energized and the cable 19 is wound up on the winch 20. At first the rod 22 is pulled through the rungs 18, taking up the slack in the cables 25. On engagement of the hook bar 24 with the lever device 33, the hook bar 24 moves the lever device 33 to engagement with the bar 32 with subsequent movement of the frame 31 and release of all of the stanchions 26 from their restraining release members 28 and 30.

The drag lever 17 restrains free movement of the cable lower flight 9 until the stanchions 26 have been pulled to the rungs 18, as in FIG. 5.

The animals are now in alignment with an opening into the barn 10 and are pulled clear of the barn 10 by the winch 20. A stop 40 on the station 11 is engageable by the first stanchion 26 to de-energize the motor 21.

It is to be understood that other conventional animal holding means may be substituted for the stanchions 26, and that any animal or animals, appropriately held by such means, may be evacuated by the device of the present invention. Further, numerous changes and modifications may be made in the device, if coming within the scope of the invention as defined by the annexed claims.

What is claimed is:

1. In combination with an animal holding barn, a stanchion in said barn, releasable support means securing said stanchion in said barn, and endless cable extending between said barn and a remote station, a winch secured to said station, a pull cable having a portion adjacent one end wound on said winch, a pull rod secured to the free end of said pull cable and supported on one of the flights of said endless cable, and a lead cable connecting each stanchion to said pull rod.

2. The apparatus according to claim 1 together with heat responsive means in said barn operatively connected to said winch for driving the latter upon increase of heat in said barn.

3. A livestock evacuation device of the character described, comprising a plurality of elongated stanchions in which is placed the head of livestock, each elongated stanchion having each end secured to a release member by means of an eye formation, each said release member in turn being secured to one of the horizontal members of a frame that is composed of the said horizontal members and a vertical member, the said horizontal members and said vertical member being formed from one continuous piece of material and a plurality of cables and an electric motor having a winch on one end of the shaft of the said electric motor, the said winch operating one of the said cables and thereby horizontally moving the said stanchions by means of a separate lead cable having one end connected to the upper eye formation of each one of the said stanchions and livestock having their head secured in the said stanchion which move the said livestock out of any barn in which the major part of the said livestock evacuation device may be located when any heat from a fire may set off a thermal responsive switch located in the said barn, the said thermal responsive switch being connected to the source of power operating

the said electric motor which is located at a predetermined distance away from the said barn.

4. A livestock evacuation device of the character described, comprising a plurality of elongated stanchions in which is placed the head of livestock, each elongated stanchion having each end secured to a release member by means of an eye formation, each said release member in turn being secured to one of the horizontal members of a frame that is composed of the said horizontal members and a vertical member, the said horizontal members and said vertical member being formed from one continuous piece of material and a plurality of cables and a drag lever having weights on one end thereof, the said drag lever providing a means of adjusting the drag on the said cables and an electric motor having a winch on one end of the shaft of the said electric motor, the said winch operating one of the said cables and thereby horizontally moving the said stanchions by means of a separate lead cable having one end connected to the upper eye formation of each one of the said stanchions and livestock hav-

ing their head secured in the said stanchions which move the said livestock out of any barn in which the major part of the said livestock evacuation device may be located when any heat from a fire may set off a thermal responsive switch located in the said barn, the said thermal responsive switch being connected to the source of power operating the said electric motor which is located at a predetermined distance away from the barn.
